Des. 190,692
Patented June 20, 1961

190,692

MOTION PICTURE CAMERA

Koji Sho, Tsurumi-ku, Yokohama City, Kanagawa-ken,
and Tomoji Okada, Nishi-Nakanobu, Shinagawa-ku,
Tokyo, Japan, assignors to Nippon Kogaku K.K.,
Tokyo, Japan, a corporation of Japan

Filed Mar. 21, 1961, Ser. No. 64,424

Term of patent 14 years

(Cl. D61—1)

FIG. 1

FIG. 2

FIG. 3

FIG. 4

FIG. 1 is a perspective view showing the top, the front, and the left side of a motion picture camera, embodying our new design;

FIG. 2 is a perspective view showing the front and right side thereof;

FIG. 3 is an elevational view showing the rear side thereof; and

FIG. 4 is a plan view showing the top thereof.

We claim:

The ornamental design for a motion picture camera as shown.
